FRAME FOR A BRUSH

Ray Rice Hutcheson, Belleville, N. J., assignor to Ox
Fibre Brush Co., Inc., Frederick, Md., a corporation of Delaware

Application May 12, 1955, Serial No. 35,952

Term of patent 14 years

(Cl. D9—2)

Fig. 1 is a front elevational view showing the frame for a brush embodying my design;

Fig. 2 is a side view;

Fig. 3 is a longitudinal sectional view taken on line 3—3 of Fig. 1; and

Fig. 4 is a transverse sectional view taken on line 4—4 of Fig. 1, showing my new design.

I claim:

The ornamental design for a frame for a brush, as shown.
